UNITED STATES PATENT OFFICE

WALTER H. WANGELIN, OF ST. LOUIS, MISSOURI

JOLTER

Application filed June 16, 1930. Serial No. 461,416.

This invention relates generally to jolters of the type employed in foundries for jolting flasks so that the sand will be firmly packed therein, and particularly to an improved jolter of this type which is so constructed and arranged that the load thereon is partly counterbalanced, the predominant object of the invention being to provide a jolter which is so constructed that the necessary power applied to elevate the flask during the jolting operation is proportionately less than was the case heretofore when the entire load of the flask was elevated by power applied thereto.

Another important object of the invention is to provide a jolter of the type referred to which instead of jolting the flask by causing the flask supporting element thereof to be stopped abruptly at the bottom of its downward movement as heretofore, includes movable jolting means which strikes the flask supporting element a sharp blow. Because of this arrangement the jolting operation is performed in a much more efficient and complete manner than heretofore.

Figure 1 is a view of my improved jolter showing same partly in elevation and partly in horizontal section.

Figure 2 is a section on the staggered line 2—2 of Figure 1.

Figure 3 is a section on line 3—3 of Figure 1.

Figure 4 is a section on line 4—4 of Figure 1.

Figure 5 is a fragmentary sectional detail illustrating a modified form of the invention.

In the drawings, wherein is shown for the purpose of illustration, merely, two embodiments of the invention, A designates the improved jolter generally, said jolter comprising a suitable base 1 which is provided with pairs of upstanding bearings 2 and 2'. The bearings 2 support a shaft 3 which extends transversely of the jolter, said shaft 3 being divided at its approximate center and the adjacent inner ends of said shaft being connected by a coupling element 4 (Figure 1).

The inner end portions of the sections of the

shaft 3 are extended into apertures 5 formed in the coupling element 4.

The bearings 2', referred to, support a shaft 6, which, like the shaft 3, extends transversely of the jolter and is divided at its approximate center. The inner ends of the sections of this shaft 6 are connected by a coupling element 7, the adjacent inner end portions of said shaft sections being extended into apertures 8 in said coupling element. 55 The coupling elements 4 and 7 are arranged in alinement with respect to each other, and each coupling element is provided with an opening 9 formed therethrough, the openings 9 being extended at an approximate right angle with relation to the direction of extension of the shafts 3 and 6. The openings 9 are preferably provided with bushings 10, and 11 designates a shaft which is supported for rotation in the bushed openings 9 of the coupling elements. The shaft 11 is the power shaft of the jolter, said shaft, in the drawings, being provided with an operating wheel 12 with the aid of which rotary motion may be applied thereto. This operating wheel 12 is illustrated, merely, for convenience, it being obvious that instead of employing an operating wheel the shaft 11 may be rotated by any suitable power element. 60 65 70 75

Pivottally supported by the shaft 3 is a 80 jolting member 13 and pivottally supported by the shaft 6 is a similar jolting member 14. When viewed in plan as shown in Figure 1 each of the jolting members is substantially 85 U-shaped; that is to say, a portion 15 of each thereof extends transversely of the jolter and bifurcated legs 16 extend outwardly from said portions 15. The shafts 3 and 6 extend through openings formed in the legs 16 of the jolting members and in this manner 90 said jolting members are pivottally supported by said shafts. Fixed to the arcuate faces 17 at the inner ends of the jolting members 13 and 14 are pairs of toothed segments 18, each pair of segments comprising a segment 95 fixed to the jolting member 13 and a similar segment fixed to the jolting member 14 the teeth of which mesh with the teeth of the first mentioned segment. The toothed segments 18 serve to compel the jolting members 100

13 and 14 to move in unison when pivotal movement is imparted thereto.

19 designates the flask support of the improved jolter, said flask support comprising frame members 20 which support a plate 21. Fixed to the frame members 20 and plate 21 and extended transversely of the direction of extension of the frame members and at opposite edges of the plate are bar-like elements 22 which are provided at their opposite ends with downwardly extended portions 23. At the lower end thereof each of the extensions 23 is provided with a bearing portion 24 (Figure 2) through which an opening 25 is formed. The downwardly extended portions 23 at one side of the flask support 19 are pivotally connected to the outer ends of the legs 16 of the jolting member 13 by means of pins 26 which pass through the openings 25 and through similar openings in said legs 16, while the downwardly extended portions 23 at the opposite side of the flask support are similarly pivotally connected to the outer ends of the legs 16 of the jolting member 14 by pins 27. It is obvious in view of this arrangement that when the inner ends of the pivotally supported jolting members 13 and 14 are moved downwardly the outer ends of said jolting members will be moved upwardly whereby corresponding upward movement will be imparted to the flask support. It is likewise plain that when the inner ends of the jolting members are permitted to move upwardly the flask support will move downwardly. The jolting members 13 and 14 are provided with openings 28 through which the power shaft 11 extends and because of the pivotal movement to which said jolting members are subjected, these openings have the approximate shape illustrated in Figure 3.

At the opposite ends of the portions 15 of the jolting members 13 and 14, said jolting members are provided with screwthreaded openings 29 and at the upper end of each of these openings a bumper 30 formed of rubber or other suitable material is arranged. The lower end of each of the bumpers 30 contacts with a nut 31 (Figure 2) which is screwed in the associated screw-threaded opening 29 and the bumper 30 may be adjusted outwardly and inwardly with respect to the screw-threaded opening by manipulating the nut 31. 32 designates a hollow lock-nut which is adapted to lock the associated nut 31 in place, said lock-nut being hollow to permit of a screwdriver being inserted therethrough for the purpose of rotating the nut 31. Arranged in vertical alinement with the bumpers 30 are portions 33 which extends downwardly from the elements 22, each of said portions 33 being provided at its lower end with a head 34.

Pivottally suspended from the inner ends 65 of the jolting members 13 and 14 is a struc-

ture 35 which supports a roller 36 at its lower end. The structure 35 comprises a pair of arms 37 which are pivoted at their upper ends to the jolting member 13 and a pair of similar arms 38 which are pivoted at their upper ends to the jolting member 14. The pivotal connection between the arms 37 and 38 and the jolting members 13 and 14 is affected by bars 39 one of which is interposed between the arms of each pair of arms. These bars 75 are provided each with reduced end portions 40 of circular cross-section which extend through apertures in the arms and are seated in recesses 41 formed in the jolting members (Figure 4). At the lower ends of each pair 80 of arms a bar 42 is interposed between said arms and this bar, also, is provided with reduced end portions 43 which extend into apertures in the lower end portions of the arms so that said bar 42 is capable of rotary motion 85 with respect to said arms. The roller 36 is mounted on a rod 44 which is supported by the bars 42 associated with the oppositely disposed pairs of arms 37 and 38. In view of the pivotal arrangement of the structure 35 90 it is plain that the roller 36 may move upwardly and downwardly in a straight line while the upper end portions of the arms 37 and 38 move in an arc of a circle with the inner end portions of the jolting members 13 95 and 14. Fixedly mounted on the power shaft 11 so that it will contact with the roller 36 is a cam 45 which is shaped approximately as illustrated in Figure 4.

In the operation of my improved jolter 100 the flask to be jolted is arranged on the flask support 19. The power shaft 11 is then rotated and as the high portion of the cam 45 moves in contact with the roller 36 the inner ends of the jolting members are drawn downwardly. This will have the effect, as already stated, of raising the outer ends of the jolting members whereby the flask support and the flask thereon will be elevated. When the flask support 19 has reached the top of its 105 upward movement the high portion of the cam 45 will pass beyond the roller 36 and gravity will cause the flask and flask support to move downwardly at a fast rate of speed. The downward movement of the 110 flask support will, of course, move the outer ends of the jolting members 13 and 14 downwardly because of the pivotal connection between these parts and such downward movement of the outer ends of said jolting members will result in the inner ends thereof being moved upwardly. The heads 34 of the portions 33 of the flask support move downwardly with said flask support, and the bumpers 30 carried by jolting members 13 120 and 14 move upwardly with the inner end portion of said jolting members, and when the flask support reaches the approximate bottom of its movement the bumpers 30 strike the heads 34 a sharp blow. The effect of this 125

upwardly directed blow coming at a time when the flask is moving downwardly causes the sand to be compacted in the flask in a very efficient manner and eliminates the necessity for the heavy jar heretofore thought essential in the operation of jolting machines.

5 In the form of the invention illustrated in Figure 5, I eliminate the pivoted structure 35 and secure the roller 36 directly to the flask support 19'. Aside from this change 10 a jolter which includes the structure illustrated in Figure 5 would be constructed just as is the jolter illustrated in Figures 1 to 4 inclusive.

15 An important feature of this invention resides in the fact that the portions 15 of the jolting members 13 and 14 are made quite heavy and, therefore, these portions serve to counterbalance the weight of the flask support 19 and the flask thereon. These portions 20 15 of the jolting members may be of such weight that the combined weight of the flask support and flask outweigh said portions 15 only slightly, and the power necessary to 25 elevate the flask support and flask need be sufficient only to lift the difference between the combined weight of the flask support and flask, and said portions 15. Thus in addition to the advantage of producing a jolter 30 which will more efficiently perform its function, a great saving in energy is realized and smaller equipment may be used to perform the tasks formerly necessitating the use of larger and more expensive equipment.

35 So that the weight of the portions 15 of the jolting members 13 and 14 may be regulated, I provide wells 46 in which suitable weights 47 may be located.

While I show in the drawings and describe 40 in the specification a precise means for elevating the flask support, I wish it to be understood that the invention is not limited to the use of such means as any suitable means for elevating the flask support may be employed. 45 In other words the invention in its broadest aspect comprises a jolter of any suitable construction, which is provided with one or more pivoted members which serve to counterbalance the flask support and the load thereon, or 50 counterbalance the flask support and its load and act as jolting elements.

I claim:

1. A jolter comprising a flask support, means for elevating said flask support, said 55 means including a pivotally supported member having a portion for subjecting said flask support to a sharp blow, said portion being movable upwardly into sharp contact with the flask support when said flask support is 60 moving downwardly, and means for pivotally connecting said pivotally supported member to said flask support.

2. A jolter comprising a flask support, means for elevating said flask support, said 65 means including a pivotally supported mem-

ber having a portion for subjecting said flask support to a sharp blow upon downward movement of said flask support, said portion of said pivotally supported member constituting a counterweight for said flask support 70 and being movable upwardly into sharp contact with the flask support when said flask support is moving downwardly, and means for pivotally connecting said pivotally supported member to said flask support.

3. A jolter comprising a flask support, means including a cam for elevating said flask support, a pivotally supported member having a portion movable in a direction opposite to that in which the flask support moves for subjecting said flask support to a sharp blow upon downward movement of said flask support, said portion of said pivotally supported member constituting a counterweight for said flask support, and 80 means for pivotally connecting said pivotally supported member to said flask support.

4. A jolter comprising a flask support, means including a cam for elevating said flask support, a pivotally supported member 90 having a portion movable in a direction opposite to that in which the flask support moves for subjecting said flask support to a sharp blow upon downward movement of said flask support, said cam being cooperable 95 with said pivotally supported member for the purpose of imparting movement thereto, and means for pivotally connecting said pivotally supported member to said flask support.

5. A jolter comprising a flask support, means including a cam for elevating said flask support, a pivotally supported member having a portion movable in a direction opposite to that in which that flask support 105 moves for subjecting said flask support to a sharp blow upon downward movement of said flask support, said cam being cooperable with said pivotally supported member for the purpose of imparting movement thereto, means 110 for pivotally connecting said pivotally supported member to said flask support, said portion of said pivotally supported member constituting a counterweight for the flask support.

6. A jolter comprising a flask support, means for elevating said flask support, a pair of pivotally supported members having portions movable in a direction opposite to that in which the flask support moves for subjecting said flask support to sharp blows upon downward movement of said flask support, means for pivotally connecting said pivotally supported members to said flask support, and interengaging means on said pivotally supported members for compelling movement thereof in unison.

7. A jolter comprising a flask support, means for elevating said flask support, a pair 120 of pivotally supported members having por-

- tions movable in a direction opposite to that in which the flask support moves for subjecting said flask support to sharp blows upon downward movement of said flask support,
- 5 means for pivotally connecting said pivotally supported members to said flask support, and interengaging means comprising toothed segments on said pivotally supported members for compelling movement thereof in unison.
- 10 8. A jolter comprising a flask support, means including a cam for elevating said flask support, a pair of pivotally supported members having portions movable in a direction opposite to that in which the flask support moves for subjecting said flask support to sharp blows upon downward movement of said flask support, and a roller pivotally suspended from said pivotally supported members with which said cam contacts whereby
- 15 said pivotally supported members are subjected to movement by said cam.
9. A jolter comprising a flask support, a pair of jolting members, shafts for pivotally supporting said jolting members, a power shaft, means supported by the first mentioned shafts for rotatably supporting said power shaft, and a cam on said power shaft for imparting vertical movement to said flask support.
- 20 10. A jolter comprising a flask support, a pair of jolting members, shafts for pivotally supporting said jolting members, a power shaft, means supported by the first mentioned shafts for rotatably supporting said power
- 25 shaft, a cam on said power shaft for imparting vertical movement to said flask support, and means for pivotally connecting said jolting members to said flask support.

In testimony whereof, I have hereunto set
40 my hand.

WALTER H. WANGELIN.
